(57) **CLAIM**

We claim the ornamental design for a charging circuit control device, as shown and described.

DESCRIPTION

FIG. 1 is a front and top perspective view of a charging circuit control device of the present invention;
FIG. 2 is a front view thereof;
FIG. 3 is a rear view thereof;
FIG. 4 is a top view thereof;
FIG. 5 is a bottom view thereof;
FIG. 6 is a first side view thereof;
FIG. 7 is a second side view thereof; and,
FIG. 8 is a top view thereof, showing unclaimed environmental structure.
The broken lines shown represent unclaimed subject matter and form no part of the claimed design.
